ANDRE' JOSSE

BY *Maurice L.*

ATTORNEY

UNITED STATES PATENT OFFICE.

ANDRÉ JOSSE, OF ETAMPES, FRANCE.

DEVICE FOR MAKING WIRE BANDS FROM WHICH WHALEBONES ARE MADE.

Application filed April 11, 1923. Serial No. 631,482.

To all whom it may concern:

Be it known that I, ANDRÉ JOSSE, a citizen of the French Republic, and residing in Etampes, Seine-et-Oise, France, have invented certain new and useful Improvements in and Relating to a Device for Making Wire Bands from Which Whalebones are Made, of which the following is a complete specification.

10 This invention relates to artificial whalebones such as used for instance for stays or corsets, and an object of my said invention is to use for the manufacture of the said whalebones resilient wires which are conveniently secured together so as to constitute a structure similar to flat springs.

Artificial whalebones are generally made of resilient blades such as for instance of a convenient metal such as steel, which is provided with a covering substance or coating, protecting the said steel blade against rusting. For manufacturing stays or corsets, for instance, such blades are used and conveniently distributed on the surface of the 25 said stay, thus forming an armature for the same. Such blades have the drawback not to easily permit some movements of the body, owing to the fact that said movements result in a longitudinal twisting of such blades in the longitudinal direction, and not a bending, so that the said stays cannot be provided with such an armature as would be desirable.

My invention, which waives the said drawback, consists in forming the parts of the said armature with members or parts comprising each a number of blades formed of resilient metallic wires, such as for instance steel wires which are embedded in a convenient coating which maintains the same at a convenient distance apart, whilst uniting and protecting the same, thus allowing the said blades to have the same resiliency in both transversal and longitudinal directions.

45 In the accompanying drawing which shows by way of example an embodiment of a machine for the manufacture of the said blades:

Fig. 1 is a general side view of the 50 machine,

Fig. 2 is a cross-section of a drawplate box hereafter referred to,

Fig. 3 is a transverse cross-section of the wire-guide along the line A—A of Fig. 2,

Fig. 4 is a vertical cross-section of a regulating device for the unrolling device of the wire,

Figs. 5 and 6 show in cross-section modifications of drawplate for the manufacture of different springs.

The steel wires which are to constitute armature of the spring are carried on bobbins in a number corresponding to that of the wires constituting the spring (five in the example shown on the drawing) and every wire passes over a regulating brake 2, each formed, as more particularly shown in Fig. 4, by a group of two conveniently shaped rollers 3, 4. The roller 4, carried on a stationary spindle 5 comprises a protruding circular rib which forces the wire 6 into a circular groove provided in the upper roller 3 which is slidably carried in holes 7 provided in a common bearing 8. A spring 9, provided with a regulating screw 10 allows the pressure exerted upon the wire 6 by the group of rollers to be conveniently determined.

The wires 6 coming from the regulating brake 2 pass over a drum 11 carrying on its circular surface parallel grooves equal in number to the wires 6, and the latter then pass between two rollers 12 which regulate the distance apart of the said wires.

In line with the said rollers is arranged a drawplate box 25 in which the group of wires is to receive the coating; then the band constituted by the said wires coated passes into a drying chamber 14, provided with convenient guiding drums 15.

After its passage in the drying chamber, the complete band 16 passes in a pulling device comprising a group of two endless belts 17, 18 before rolling upon a drum 19.

The drums 11 and 19, together with the endless belts 17, 18, are driven by a convenient motor, not shown on the drawings, which controls a shaft 20 carrying the pulleys which control the several belts for the members of the machine.

The drawplate itself 13 is constituted, as shown in Figs. 5 and 6, by a metallic disc, for instance of steel, which has openings 21 arranged side by side, as more particularly

seen in Fig. 5, and in relation with each other for forming a continuous mortise in the transverse direction, the dimension of which is conveniently larger than the diameter of the wires 6 in order to allow a convenient coating substance to be brought around the same.

The said drawplate 13 is embedded in a sleeve 24, and is maintained in its convenient position by a screw 23. The sleeve 24 is secured in the box 25 by means of a nut 22.

Arranged at the mouth piece of the drawplate 13 is a cylindrical guiding piece in two parts 27, provided with longitudinal cylindrical grooves corresponding to the openings of the drawplate 13, and through which pass the wires before entering the drawplate.

The said guiding piece is fitted in a member 28 square in shape towards the drawplate, but having grooves or slots 31 allowing the coating matter to pass. The guide 27 is exactly fitted in a casing of corresponding shape of the sleeve 24, and the part 28 is thus prevented from rotating relatively to the said sleeve, while being allowed to longitudinally slide.

On the opposed end, the sleeve 24 is round and its screw-threaded part, screwed in another sleeve 29, which is rotatably secured on the box 25 by means of a nut 35, secured in position by means of a screw 30.

By turning the said sleeve 29 through the nut 35 with which there may be engaged a pin for turning it, the part 28 is caused to advance or recoil thus increasing or reducing, respectively the space comprised between the drawplate and the end of the piece 28, and thus allowing consequently more or less substance to be brought into contact with the wires.

The grooves or slots 31, of the part 28 end into a chamber 32, connected by means of a channel 33 with the forcing chamber 34 of the trough or body 26 of a hydraulic press of any convenient character which contains a convenient mass of coating substance, or conveniently connected with a tank of the said substance. A heating collar 35^a is provided on the foot of the press 26, thus enabling to increase the fluidity of the substance forced by the piston of the hydraulic press.

The operation is as follows:

The several parts occupying the position shown on the drawing, and rollers or drums 1, for instance five in number as in the instance shown, being mounted on their respective spindles in a convenient position, the wires 6 coming from the said rollers or drums, after having passed the brakes 2, pass over the grooves of the drum 11, and between the rollers 12 conveniently grooved, which keep the said wires at a convenient distance apart. The said wires then pass

through the guiding devices 27 for arriving into the openings 21 of the drawplate 13. The hydraulic press being put in motion, the coating substance contained in the trough 26 is brought through the channel 23 to the chamber 32 and the grooves 31, in the room or space existing between the drawplate 13 and the end of the guiding piece 27, and the progress of the wires is conveniently combined with that flowing of substance for obtaining at the outlet of the drawplate 13 a band the core of which is constituted by the wires, the said core being embedded in the coating substance coming from the trough 26. The said substance may be any plastic substance such as for instance cellulose acetate, celluloid, viscose, artificial india-rubber or any other, the wires which constitute the said band being thus rigidly connected with one another in their relative positions, and thus forming, after their passage in the drawplate, a band the cross-section of which nearly offers the shape of the mouth piece 21 of the said drawplate. The said band passes over the drums 15 of the drying chamber 14, where it sufficiently dries, then after the same having gone out of the said chamber, it enters between the belts, 17, 18, which, being rotated in an inverse direction owing to their contact, exert a pull on the said band, thus keeping the same under a convenient tension.

In order to insure a convenient operation of the machine, the endless belts 17, 18 rotate at a speed which is slightly higher than that of the drum 11. The said band, afterwards rolls upon the receiving drum 19, which thus winds up a length of resilient band, the drying of which is conveniently completed before the same is sheared at the given length.

The invention thus allows elastic blades to be obtained the resiliency of which is nearly the same in all directions, thus allowing the same to be twisted round their longitudinal axis, or bent in their length, which renders the said elastic blades particularly designed for the manufacture of stays or corsets or any similar clothes. The flexible band thus obtained may comprise a core formed of any convenient number of wires of steel or any other convenient metal, the said wires being either arranged side by side, or maintained at a distance apart, the said wires being maintained in their said relative position by embedding the same in the coating substance. The diameter of the wires may of course vary according to the strength of the springs to be obtained.

The shape of the drawplate 13 may differ from that shown and according to the desired result, it may, for instance, offer the arrangement of Fig. 6 if it is desire to obtain blades with plain surfaces without any transverse waves.

The invention may be applied to the manufacture of elastic or resilient blades for any use, for instance for the manufacture of springs which are to be used for the manufacture of stays or corsets.

What I claim is:

1. A device for making a wire band from which artificial whalebones are made, comprising means for laying a plurality of metallic wires side by side in spaced relation and all in the same horizontal plane, means for imparting a traveling movement to the said wires, and means for applying an adhesive substance to said wires to bind them together and form a coated flat band.
2. A device for making a wire band from which artificial whalebones are made, comprising means for laying a plurality of metallic wires side by side in spaced relation and all in the same horizontal plane, means for imparting a traveling movement to said wires, means for applying an adhesive substance to said wires to connect the wires and form a coated flat band, and a drier through which the band is passed, and means for keeping the band under tension.
3. A device for making a wire band from which artificial whalebones are made, comprising means for laying a plurality of wires side by side in spaced relation and all in the same horizontal plane, a device for applying an adhesive substance to the said wires, a draw plate through which the coated wires pass to form the same into a flat band, a drier through which the band passes, and a drawing device for feeding the band through the drier and keeping it under tension.
4. A device of the character described, comprising a plurality of rollers carrying metallic wires, brakes regulating the speed of passage of the said wires, a group of rollers regulating the position of the wires, a draw plate through which the wires pass, a hydraulic press for applying to the said wires when passing the said draw-plate, an adhesive substance, whereby the wire will be formed into a flat band, a drying cham-

ber through which the band passes, and a pulling device formed by two endless belts 50 rotating in reverse directions and delivering the finished resilient band to a receiving drum.

5. In a device of the character described, a plurality of wires carrying rollers, means 55 for imparting traveling movement of the wires, brakes for regulating the speed of the wires, a roller provided with grooves to receive the wires, rollers between which the wires pass, a draw plate box, a draw plate 60 mounted in the box, and a hydraulic press for supplying an adhesive substance to the wires as they pass to the draw plate.

6. A drawplate for coating and uniting the wires characterized by a metallic disc 65 comprising parallel openings, connected with one another thus constituting a channel the cross-section of which corresponds to the whole cross-section of the wires, plus the thickness of the coating.

7. A device for making a wire band from which whalebones are made, comprising rollers for laying a plurality of wires in spaced relation and all in the same horizontal plane, means for imparting a traveling movement to the wires, means for applying an adhesive substance to the said wires to connect and coat them, and a draw plate through which the coated wires pass to remove the surplus adhesive substance and 75 form a flat band.

8. A device for making a wire band from which whalebones are made, comprising a plurality of rollers carrying wires, a group 85 of rollers for laying the wires in spaced relation and all in the same horizontal plane, means for applying an adhesive substance to the wires to connect and coat them, a draw plate through which the coated wires pass to remove the surplus adhesive substance and form a flat band and a drawing device for imparting a traveling movement 90 to said wires.

In testimony I have hereunto set my hand:

ANDRÉ JOSSE.
